Primary Examiner — Anhdao Doan(74) *Attorney, Agent, or Firm* — Knobbe, Martens, Olson & Bear, LLP(57) **CLAIM**

The ornamental design for a blood pressure monitor, as shown and described.

DESCRIPTION

FIG. 1 is a perspective view of a first embodiment of a blood pressure monitor embodying our new design;

FIG. 2 is top view thereof;

FIG. 3 is bottom view thereof;

FIG. 4 is a side view thereof;

FIG. 5 is another side view thereof;

FIG. 6 is a front view thereof;

FIG. 7 is a back view thereof;

FIG. 8 is a perspective view thereof in a condition of use; and,

FIG. 9 is a perspective view thereof in another condition of use.

The broken lines illustrate portions of the blood pressure monitor that form no part of the claimed design, and the additional broken lines in FIGS. 8 and 9 represent environmental subject matter and form no part of the claimed design.
